UNITED STATES PATENT OFFICE.

SAML. RAY AND M. R. SHALTERS, OF ALLIANCE, OHIO.

COMBINED CHAIR AND CRIB.

Specification of Letters Patent No. 27,069, dated February 7, 1860.

To all whom it may concern:

Be it known that we, SAMUEL RAY and M. R. SHALTERS, of Alliance, in the county of Stark and State of Ohio, have invented a 5 new and useful Combination of a Rocking-Chair and Crib; and we do hereby declare that the following is a full, clear, and exact description of the same, reference being had to the annexed drawings, making a part of 10 this specification, in which—

Figure 1 is a side sectional view of our invention, taken in the line x, x , Fig. 2. Fig. 2, an inverted plan of ditto.

Similar letters of reference indicate corresponding parts in the two figures.

The object of this invention is to combine a rocking chair and crib, in such a manner that the device, by an extremely simple adjustment, may be used in either capacity 20 equally as well as if it were made for either purpose only, thereby forming an economical and very convenient article of household furniture.

The invention consists in the employment 25 or use of a supplemental folding back and a folding seat applied to the chair and used in connection with a sliding leg and rocker frame, substantially as hereinafter described, whereby the desired end is obtained.

To enable those skilled in the art to fully 30 understand and construct our invention, we will proceed to describe it.

A, represents the bottom of the chair, which may be of a solid plank or board, or 35 formed of a frame, having a cane or rush filling, similar to the cane or rush-bottom chairs in use. To the under side of this bottom A, two parallel bars a, a , are attached; to one end of which are secured the 40 legs b, b , which support one side of the chair; said legs having a rocker c , attached to their lower ends. The bars a, a , are connected by a traverse bar d , through which a bolt e passes into the bottom A, or into any 45 permanent solid part connected therewith. The bars a, a, d , form a frame which is allowed to turn freely on the bolt e .

The bars a, a , serve the purpose of guides, 50 between which bars f, f are fitted and allowed to slide freely, said bars being retained in proper position by clips f' and the bar d . The bars f, f , are connected near their outer ends by a traverse bar g , and near the ends of the bars f, f , legs h , are attached, having a rocker i , at their lower ends, the legs h , and rocker i supporting the

side of the chair opposite to that supported by the legs b , and rocker c .

The traverse bar g , has a thumb screw j , passing through it; said screw passing into the bottom A, and preventing the casual sliding out of the bars f, f , from between the bars a, a , and also preventing the turning of all the bars on bolt e . To the front edge of the bottom A, of the chair there is a supplemental bottom B attached by joints or hinges k . This bottom B is allowed to fold over on the bottom A, and fit snugly upon it as shown clearly in Fig. 1.

C, is the back of the chair, which may be constructed in any of the usual forms. This back is attached to the permanent bottom A, and to each side of said back and to uprights l , arms D are attached. To the front part of each arm D, a supplemental 75 arm E is attached by a bolt or pivot m . The arms E may correspond in shape to the arms D, and to the disengaged ends a back or traverse frame F is attached, the latter being formed of uprights n, n , to which a 80 traverse piece o is secured.

When the device is used as a rocking chair, the supplemental bottom B is folded over on the bottom A, and the supplemental arms E are also folded back so that they 85 will be by the side of the arms D, D, and the back or frame F against the inner side of the back, C, as shown in black in Fig. 1. The bars f, f , are shoved inward to their 90 full extent between the bars a, a , as shown in black in Fig. 2, and secured in such position by the thumb screw j . In order to convert the chair into a crib, the thumb screw j , is withdrawn and the bars a, a, d, f, f, g , with the rockers c, i , are turned 95 around at right angles to their former position, and the bars f, f , are withdrawn out some distance from between the bars a, a , as shown in red, in Fig. 2. The supplemental bottom B is then turned over and outward 100 from the bottom A, and rests on the traverse bar g of the bars f, f , said bar g , being secured in proper position by screwing the thumb screw j into the supplemental bottom B. The supplemental arms E, E, are also 105 turned over and outward from the bottom A, the uprights n, n , resting on the supplemental bottom B as shown clearly in red Fig. 1. The crib is thus formed and provided with rockers and suitable side and end guards; the back C, of the chair forming one end guard, the traverse frame F the 110

other, and the arms D, E, the sides. We would remark that the legs b, h, may be secured in proper position by braces p, extending from the legs to their bars a, a, f, f.

5 Having thus described our invention what we claim as new, and desire to secure by Letters Patent, is,

The permanent bottom A, supplemental bottom B, permanent arms D, and supplemental arms E, with traverse frame F, at-

tached, and the turning and the sliding leg and rocker frames, formed of the bars a, a, d, and f, f, g, the whole being combined and arranged as, and for the purpose set forth.

SAMUEL RAY.
M. R. SHALTERS.
